UNITED STATES PATENT OFFICE.

JOHN F. O'CONNOR, OF CHICAGO, ILLINOIS, ASSIGNOR TO WILLIAM H. MINER, OF CHAZY, NEW YORK.

TWO-PART YOKE.

1,174,270.

Specification of Letters Patent.

Patented Mar. 7, 1916.

Application filed November 20, 1914. Serial No. 873,085.

To all whom it may concern:

Be it known that I, JOHN F. O'CONNOR, a citizen of the United States, residing at Chicago, in the county of Cook and State of Illinois, have invented a certain new and useful Improvement in Two-Part Yokes, of which the following is a full, clear, concise, and exact description, reference being had to the accompanying drawings, forming a part 10 of this specification.

This invention relates to improvements in two part yokes.

An object of the invention is to provide a yoke consisting of two like parts having integral means thereon for locking the parts against lateral separation, the interlocking of the parts being effected by means of tongues and grooves.

The invention furthermore consists in the 20 improvements in the parts and devices and in the novel combinations of the parts and devices, as herein shown, described or claimed.

In the drawing forming a part of this 25 specification, Figure 1 is a side elevation of a yoke embodying my improvements. Fig. 2 is a top plan view of the structure illustrated in Fig. 1. Fig. 3 is a vertical sectional view taken substantially on the line 30 3—3 of Fig. 1 and Fig. 4 is a detail side elevation of one of the yoke members and showing the inner side of the filler web having the interlocking device thereon.

In said drawing, the yoke as shown 35 comprises two like loop members 10—10, each having upper and lower arms 11—11, rear connecting portion 12 and front side wall 13, the latter being provided with an elongated coupler key slot 14. At its rear end, 40 each yoke member is provided on the inner side thereof with a filler flange or web 15 centrally located transversely of the rear connecting portion 12 which flange has an enlarged or widened front edge 16 to provide 45 a suitable bearing against the rear side of a rear follower. On the inner side of the web 15, that is the inner side when the yoke members are in assembled relation, is provided two diametrically disposed segmental 50 bosses 17 and 18, each of which extends over

an arc slightly less than 90 degrees. The member 17, as shown in Figs. 3 and 4, is provided with a laterally extending overhanging segmental flange or tongue 19 which is adapted to be seated in and interlock 55 with a correspondingly undercut segmental groove 20 formed in the corresponding member 18 of the other loop member. In other words, the overhanging flange or tongue formed on one member 17 of one yoke member is adapted to be inserted in the correspondingly shaped groove or recess in the member 18 of the other yoke member and the two parts are assembled and self locked by first placing the two yoke members 60 10—10 at an angle of approximately 45 degrees to each other, so that the bosses 17 and 18 of one member will pass into the spaces between the bosses 17 and 18 of the other yoke member. Then by swinging the 70 two yoke members 10 into alinement, it is apparent that the flange 19 of the one will engage in the groove 20 of the other and when thus positioned, lateral separation of the two yoke members is prevented. If desired, the two webs or flanges 15 may be 75 perforated as indicated at 21 and a rivet 22 passed therethrough to assist in holding the two yoke members together and to prevent the same from swinging angularly with respect to each other. As will be apparent, the means for attaching the two together are simple and may be readily cast integral with the loop members, both members being made 80 from the same pattern.

I claim:—

1. A yoke of the character described comprising two members having integral means for connecting the same and preventing lateral separation thereof, said means being 90 located at the rear of said members and comprising a plurality of interlocking tongues and grooves on each member.

2. A yoke of the character described comprising two members each having co-operating, interlocking, tongues and grooves, the parts being interlocked by swinging one member relatively to the other in planes parallel to the planes of said members.

3. A yoke for draft riggings comprising 100

two like loop members each of which, at the rear end of the inner side thereof is provided with a filler web; each of said webs having cast integrally thereon on the inner side a pair of segmental bosses having spaces therebetween, one of said bosses having a tongue and the other a groove whereby the tongue

of one boss is adapted to enter the groove of a corresponding boss on the other loop member.

JOHN F. O'CONNOR.
